UNITED STATES PATENT OFFICE.

ALFRED COPONY, OF CHICAGO, ILLINOIS, ASSIGNOR TO WILLIAM H. MINER, OF CHICAGO, ILLINOIS.

PROCESS OF MAKING DRAFT-GEAR YOKES.

1,128,295.

Specification of Letters Patent. Patented Feb. 16, 1915.

Application filed March 23, 1914. Serial No. 826,804.

To all whom it may concern:

Be it known that I, ALFRED COPONY, a subject of the Emperor of Austria-Hungary, residing in Chicago, in the county of 5 Cook and State of Illinois, have invented a new and useful Improvement in Processes of Making Draft-Gear Yokes, of which the following is a specification.

This invention relates to improvements in 10 process of making draft gear yokes.

An object of the invention is to provide a simple process involving few steps for manufacturing yokes for use in railway draft riggings, which yokes are composed 15 partly of steel castings and partly of wrought iron.

The invention furthermore consists in the improvements in the steps and novel combinations of the steps of the process herein 20 shown, described or claimed.

In the drawing forming a part of this specification are illustrated the different steps in carrying out my process, all the 25 views being in perspective.

In said drawing, Figure 1 represents a bar or strap of wrought iron such as is used in carrying out my process. Fig. 2 shows the bar or strap after the first operation thereon in which the center portion is offset 30 laterally from the main portions thereof.

Fig. 3 shows the strap of wrought iron bent back upon itself or doubled with an elongated recess in the bend. Fig. 4 shows the 35 next step in the process wherein the inner ends of the strap are bent at right angles to the main portion thereof, said ends forming one-half of the rear portion of the finished yoke. Fig. 5 shows a piece of wrought

iron cut to suitable size which is used as a 40 connecting member or clip, as hereinafter described. Fig. 6 shows the clip after the corner portions thereof have been cut out. Fig. 7 shows the next step in forming the 45 clip wherein the end portions are bent at right angles to the central portion. Fig. 8 shows the clip in its finished form. Fig. 9 shows one of the steel castings employed in the yoke and Fig. 10 shows the finished yoke wherein two of the wrought iron mem-

bers have been brought into proper position 50 relatively to each other and the clip secured in place to rigidly connect the wrought iron members and also the steel castings secured to the ends of the arms of the yoke. Figs. 55 11 to 17, inclusive, illustrate another way of

carrying out my process to form a slightly different form of yoke. Figs. 11, 12, 13 and 14 showing respectively the steps in forming the wrought iron member and corresponding respectively to Figs. 1, 2, 3 and 4; 60 Fig. 15 showing a different form of connecting member for the wrought iron straps; Fig. 16 showing one of the steel castings employed; and Fig. 17 showing the finished yoke wherein the wrought iron 65 members are firmly and rigidly connected together and the steel castings are attached to the ends of the yoke arms.

Referring now more particularly to Figs. 1 to 10 inclusive, 20 denotes a piece of wrought 70 iron cut to the proper length which is first operated upon to have the central portion 21 thereof laterally offset relatively to the main portions 22, 22. The bar is next bent to the shape shown in Fig. 3 wherein the 75 portions 22, 22 are brought together and the central portion 21 bent to form the end of the yoke arm and to provide an elongated slot 23. The rear ends of the portions 22 are next bent at right angles as indicated 80 at 24 in Fig. 4, it being understood that two wrought iron members of the form shown in Fig. 4 are provided for each yoke.

In Fig. 5 a wrought iron plate 25 is shown which first has the corner portions thereof 85 cut out to form a member of the shape shown in Fig. 6, having side wings or arms 26, 26. These wings or flanges 26 are next bent at right angles to the center portion to form a substantially U-shaped member as 90 indicated in Fig. 7. The end portions of the wing members 26 are next bent at right angles to the form shown at 27 in Fig. 8 so that the clip or connecting member assumes the form of a band. For each yoke, two 95 steel castings are provided, each of which has a longitudinally extending recess 28 therein, see Figs. 9 and 10, and an elongated boss 29 on its outer face, the bosses 29 corresponding in size and shape to the recesses 23 formed in the ends of the wrought iron members. The finished yoke is formed by rigidly securing the bent ends 100 24 of two wrought iron members together by means of the band-like clip which encircles the same as shown in Fig. 10. The steel castings are also secured to the inner sides of the arms of the yoke by inserting the bosses 29 within the recesses 23 as shown 105 in Fig. 10.

The finished yoke shown in Fig. 10 is so constructed that the wrought iron members have the same cross sectional area throughout their entire lengths, including 5 the central portions which are bent around the bosses on the castings.

Referring now more particularly to Figs. 11 to 17 inclusive, 120 represents a bar or strap of iron of suitable cross sectional area 10 and of proper length which is used to form one of the wrought iron portions of the finished yoke. The bar or strap 120 first has its central portion 121 thereof upset; thereby increasing the thickness but decreasing 15 the width relatively to the end portions 122, 122. The bar is then bent or doubled upon itself to the form shown in Fig. 13, a recess 123 being provided on account of the metal having previously been upset, it being also 20 noted that the thickened portion of the metal surrounds said recess. The rear or inner ends of the wrought iron strap are then bent at right angles to the body thereof to the form shown at 124, Fig. 14. Two 25 wrought iron members of the form shown in Fig. 14, are provided for each yoke and to rigidly and permanently connect the same together a connecting member 125 is provided of the form shown in Fig. 15, the latter being punched, as at 126, for rivets. For 30 each yoke, two steel castings are provided, each of which is of the form shown in Fig. 16. Each steel casting is longitudinally slotted as shown at 128 and is provided on 35 its outer side with an elongated boss 129 surrounding said slot, the bosses 129 corresponding in size and shape to the recesses 123 formed in the ends of the arms of the yoke. The two wrought iron members for 40 each yoke are connected by means of the plate 125 which is put in the position shown in Fig. 17 and riveted to the bent ends 124 as there shown. The steel castings are also at-

tached to the ends of the arms of the yoke, on the inner sides thereof, with the bosses 45 129 inserted in the recesses 123.

It will be noted that the yoke shown in Fig. 17, has the arms thereof of uniform width throughout their entire length although the wrought iron straps are not of 50 uniform cross section throughout.

From the preceding description, it will be seen that I have provided a process of manufacturing combined cast steel and wrought iron yokes of few steps and one which does 55 not require the use of any complicated or expensive machinery.

Although I have herein shown and described what I now consider the preferred manner of carrying out my process, yet 60 it will be understood that changes may be made in the steps of the process without departing from the spirit of the invention and all such changes or variations are contemplated as come within the scope of the 65 claim appended hereto.

I claim:

The herein described process of making combined cast metal and wrought iron yokes for railway car draft riggings which consists in providing two cast members, each having a boss thereon, and two straps of wrought iron, each strap being first offset at the middle thereof and then doubled upon itself to provide an elongated recess at the 70 bend to receive and fit one of the bosses on said castings, then uniting said castings to the wrought iron straps with the bosses in the recesses thus formed and also uniting the wrought iron straps together. 75

Signed this 13 day of March, 1914, in the presence of two witnesses.

ALFRED COPONY.
